(57) **CLAIM**

The ornamental design for a drop-prevention strap for a rolled product, as shown and described.

DESCRIPTION

FIG. 1 is a front elevational view of a drop-prevention strap for a rolled product showing our new design with a carabiner on one portion connected to a D-ring on another portion; FIG. 2 is a side elevational view thereof shown for clarity with the carabiner disconnected from the D-ring; FIG. 3 is a side, front, and top perspective view thereof shown with the carabiner connected to the D-ring; and, FIG. 4 is a side, front, and top perspective view thereof shown installed on a structure and holding a rolled product, where the objects in broken lines are shown for the purpose of illustrating environment and form no part of the claimed design.
